UNITED STATES PATENT OFFICE

EDWARD M. DEEMS, OF FOREST HILLS, AND WILLIAM H. B. LAVARACK, OF PINE BUSH, NEW YORK, ASSIGNEES TO RAILROAD ACCESSORIES CORPORATION, OF NEW YORK, N. Y., A CORPORATION OF NEW YORK

RAIL BOND

Application filed February 27, 1926. Serial No. 91,022.

This invention relates to electrical conductors, particularly to such conductors used as electrical bonds and more especially as rail member bonds.

5 A principal object of this invention is the production of a bond of the type described which is especially adapted for bonding from one rail head or ball to an adjacent rail head or ball or from a rail head or ball to an adjacent joint or fish plate.

10 Other objects and advantages will appear as the description of the particular physical embodiments selected to illustrate the invention progresses and the novel features of the invention will be particularly pointed out in the appended claims:

15 In describing the invention and the particular physical embodiments selected to illustrate the invention, reference will be had 20 to the accompanying drawing illustrating particular preferred physical embodiments of the invention selected to illustrate the invention and wherein the same characters of reference designate corresponding parts 25 throughout the several views, and in which:

Figure 1, illustrates a side elevation of a fragment of two rails with a rail bond embodying the invention in place thereon; Fig. 2, is a cross sectional view on the planes indicated by the line 2—2 of Fig. 1; Fig. 3, is a part plan and part sectional view of a fragment of a bond embodying the invention showing the structure thereof in detail; Fig. 4, is a plan view illustrating a modified form 30 of bond embodying the invention; Fig. 5, is a view showing another modified form; Fig. 6, is a detail view illustrating another modified construction; Fig. 7, is a view showing another modified construction; Fig. 8, is a side 35 elevational view, similar to Fig. 1, showing a modified application.

40 In the drawings, particularly Fig. 1, 1 designates one rail and 2 an adjacent substantially abutting rail. For the purpose of 45 illustrating the use of the invention selection might well be made of any two adjacent structures which might be called rail members so that when reference is hereinafter made to rail it may be considered equivalent 50 to rail member and vice versa.

In order to electrically connect the rail 1 with the rail 2 it is preferred to make electrical connection from rail head 3 to rail head 4. In order to do this it is preferred to use a conductor 5 and it is preferred to use a 55 stranded somewhat flexible conductor made of a relatively soft metal such as copper.

In order to mechanically protect the conductor 5 it is preferred to surround conductor 5 preferably with a helically wound member 60 as 6. The member 6 is preferably made of a relatively hard material quite resistant to corrosion and to the usual abrasion to which it will be subjected in use, and a material of a very considerable elasticity. It is preferred 65 to use a phosphor bronze which has the qualities specified.

To connect the conductor 5 to the rail heads I prefer to use an enlarged member as 7. This enlarged member is formed with a passage 8. In order to connect conductor 5 to this enlarged member 7, it is preferred to pass the end portion of the conductor 5 through the passage and then solder it in place. By solder, is meant to be designated any of the 75 well known processes which go by the name of soldering, tinning, autogenous soldering or electric welding.

It is preferred to form a cavity 9 at the opening of the passage 8 and to have this 80 cavity of greater diameter than the diameter of the passage. This cavity is preferably filled with soft metal while molten and this metal firmly attaches itself both to the enlarged member and to the conductor, as 85 shown in Fig. 6. By this construction vibration to which the conductor is subjected in practice is rendered practically incapable of causing the conductor to break, as is usual, at the line of contact of the conductor with the enlarged member because the soft metal apparently absorbs the vibration and so prolongs the life of the conductor.

In the preferred form of bond the helical 90 member 6 surrounding the conductor 5 extends from one enlarged member, as 7, to the other at the other end of the bond as shown in Fig. 1, although, if desired, the helical member may be used without the central por- 100

tion, as shown in Fig. 4, in which 10 is one end portion and 11 is the other.

In the preferred form of bond the enlarged member 7 forms part of a plug which has a tapered portion 12 which is driven into a cavity as 13, Fig. 2, of the rail member. In order to secure the plug firmly it is formed with a cavity 14 of uniform bore into which a dowel 15 is driven by driving the plug into the cavity, as 13, and which expands the walls of the plug into firm contact with the walls of the cavity in the rail chamber.

The dowel in practice is shipped in place as shown in Fig. 3. To facilitate this the dowel is made with a tapered portion 16 and a portion of reduced diameter 17 of the same size as the diameter of the cavity 14. This reduced portion at the small end of the tapered portion substantially forms a chamfered shoulder 18, which being positioned as shown in Fig. 3 when the plug is inserted in a rail cavity and driven, immediately begins to expand the walls of the plug. In order to retain the dowel in place when shipping, it is knurled for a short distance on the reduced portion, as at 19.

In the preferred construction of bond the helical member 6 where it bears against the enlarged member 7 is seated within the cavity 9 and in addition the soft metal 20 surrounding the conductor 5 and filling the cavity 9 is attached to and fills several of the convolutions of the helix 6.

Although our preferred form of construction is as shown by Figs. 1, 2 and 3, nevertheless many situations would be well suited to the form of construction shown in Fig. 8, which is identical with that shown in Figs. 1, 2 and 3 except that the enlarged member 7 has no tapered portion and is formed to be welded or brazed directly to the face of the head or ball of the rail member.

Although most situations call for a rail head to rail head connection, nevertheless the improved bond may be connected between any two rail members, as shown in Fig. 7, in which 21 designates a fish plate or angle bar, as one of the rail members.

In Fig. 5 has been shown a construction in which the conductor 5 has been eliminated. This construction would be suitable where but small conductivity is required, although if the material forming the helix is of large enough cross section any required conductivity could be provided for.

The bond hereinbefore described because containing the soft, flexible stranded conductor 5 is of good conductivity. By being surrounded by the helix the conductor 5 when subjected to usual distortion will be bent without abruptness and in easy sweeping arcs of comparatively long radius which tends to prolong the life of the bond. The helix 6 further protects the soft metal of the bond from mechanical injury and from abrasion by rub-

bing against a rail member such as an adjacent fish plate. The soft metal in the cavity 9 absorbs the usual vibration and in connection with helix 6 practically prevents failure of the conductor in service at a line of contact of the conductor with the enlarged member 7. A bond in the preferred form is conveniently installable, merely by forming a cavity in the rail member with an ordinary drill and is easily removable by inserting a tool such as a claw bar in the space between the portion 7 and the rail head. The bond may be shipped complete with the dowel pins 15 in place and if the knurling 19 is not entirely sufficient to hold the dowels in place it may be aided by dipping the plug in molten metal as tin after the dowels have been put in place whereby the dowel and plug will be additionally held together by the soldering action of the tin.

Although there has been particularly described the preferred physical embodiment of the invention and modified forms thereof, nevertheless, it is desired to have it understood that the forms selected are merely illustrative but do not exhaust the possible physical embodiments of the idea of means underlying the inventions.

What is claimed as new and desired to secure by Letters Patent of the United States, is:

1. In a rail bond for electrically connecting adjacent rail members, formed each with a cavity in combination: a plug for insertion in a cavity of one rail member; a plug for insertion in a cavity of another adjacent rail member, each of said plugs formed with a passage therein and a cavity of larger diameter at an entrance to the passage; a conductor having one end portion positioned in the passage of one plug and the other end portion in the passage of the other plug and securely soldered to each plug; a helically wound electrically conducting member surrounding the conductor and having one end seated in the cavity of one plug and the other end seated in the cavity of the other plug.

2. In a rail bond for electrically connecting adjacent rail members, formed each with a cavity in combination: a plug for insertion in a cavity of one rail member; a plug for insertion in a cavity of another adjacent rail member, each of said plugs formed with a passage therein and a cavity of larger diameter at an entrance to the passage; a conductor having one end portion positioned in the passage of one plug and the other end portion in the passage of the other plug and securely soldered to each plug; a helically wound member surrounding the conductor and having one end seated in the cavity of one plug and the other end seated in the cavity of the other plug, and soldered to each plug.

3. In a rail bond for electrically connecting adjacent rail members, formed each with

- a cavity in combination: a plug for insertion in a cavity of one rail member; a plug for insertion in a cavity of another adjacent rail member, each of said plugs formed with a passage therein and a cavity of larger diameter at an entrance to the passage; a conductor having one end portion positioned in the passage of one plug and the other end portion in the passage of the other plug and securely soldered to each plug; a helically wound member surrounding the conductor and having one end seated in the cavity of one plug and the other end seated in the cavity of the other plug and having soft metal surrounding the conductor and filling the cavity and attached both to the conductor and the plugs. 70
4. In a rail bond for electrically connecting adjacent rail members formed each with a cavity in combination: a plug for insertion in a cavity of one rail member; a plug for insertion in a cavity of another adjacent rail member, each of said plugs formed with a passage therein and a cavity of larger diameter at an entrance to the passage; a conductor having one end portion positioned in the passage of one plug and the other end portion in the passage of the other plug and securely soldered to each plug; a helically wound member surrounding the conductor and having one end seated in the cavity of one plug and the other end seated in the cavity of the other plug, and having soft metal surrounding the conductor and filling the cavity and attached both to the conductor and the plugs. 80
- 20 5. In a rail bond for electrically connecting adjacent rail members, in combination: an enlarged member for attachment to one rail member; an enlarged member for attachment to another adjacent rail member, each of said enlarged members formed with a passage therein and a cavity of larger diameter at an entrance to the passage; a conductor having one end portion positioned in the passage of one enlarged member and the other end portion in the passage of the other enlarged member and securely soldered to each enlarged member; a helically wound member surrounding the conductor and having one end seated in the cavity of one enlarged member and the other end seated in the cavity of the other enlarged member. 85
- 25 6. In a plug for insertion in a rail member cavity the combination of a tapered portion circular in cross section and formed with a cavity of uniform diameter of a dowel for engagement with said last named cavity circular in cross section and having a tapered portion and a portion of reduced diameter thus forming substantially a shoulder, said portion of reduced diameter having substantially the diameter of the cavity of the plug. 90
- 30 7. As a dowel for a plug for a rail bond, 95
- 35 8. A body circular in cross section throughout, tapered and having a portion of reduced diameter adjacent the smaller end of the tapered portion, and having a portion of the reduced diameter portion knurled. 100
- 40 9. EDWARD M. DEEMS. 105
- 45 10. WILLIAM H. B. LAVARACK. 110
- 50 11. 115
- 55 12. 120
- 60 13. 125
- 65 14. 130
